UNITED STATES PATENT OFFICE.

MERTON E. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOLE-FITTING MACHINE.

Application filed October 18, 1919. Serial No. 331,580.

To all whom it may concern:

Be it known that I, MERTON E. JOHNSON, a citizen of the United States, residing at Beverly, in the county of Essex and State 5 of Massachusetts, have invented certain new and useful Improvements in Sole-Fitting Machines; and I do hereby declare the following to be a full, clear, and exact description of the invention, such as will enable 10 others skilled in the art to which it appertains to make and use the same.

This invention relates to sole fitting machines and more particularly to such machines for preparing soles having pointed 15 toes for the succeeding operations of lip turning and inseaming. A machine of this type is disclosed in Letters Patent of the United States to John B. Hadaway, No. 1,087,578, dated February 17, 1914.

20 The primary object of the present invention is to improve the machine of the Hadaway patent to provide a proper fitting for both turn soles and welt insoles and especially welt insoles of the Economy type. Another object is to improve the prior machine 25 in such manner as to enable it to be used for slitting the channel flap at points other than the toe, for example at the inside ball where the curve of the channel is most abrupt.

30 Accordingly one feature of the present invention comprises improved knives for making the incisions in the sole, as well as the mounting of these knives, enabling the machine to make the kind of incision required 35 for the new sole which is produced. Another feature of the invention comprises an improved mounting of the gage members for positioning the sole relative to the knives permitting their withdrawal from

40 above the work support. This provides an unobstructed surface in front of the knives and permits manipulation of the sole to present any part of its margin for the incising action thereof.

45 To the accomplishment of these objects and such others as may hereinafter appear, as will readily be understood by those skilled in the art, the invention comprises the features and combinations of parts hereinafter 50 described and particularly pointed out in the appended claims.

The invention will be best understood from a description of the preferred embodiment thereof, illustrated in the accompany-

ing drawings, in which Figure 1 is a side 55 elevation of the improved machine, the working head being shown in section; Fig. 2 is a detail in front elevation, of the working head and work support, the former being shown lowered with the knives in the 60 sole; Fig. 3 is a side elevation, in section, of the working head and the work support; Figs. 4 and 5 are plan views of the work support illustrating respectively the sole 65 gages when located for incising the toe and the side of a sole; Fig. 6 is a detail in side elevation of the mechanism for operating the sole gages, said gages being shown removed from the table as in Fig. 5; and Fig. 7 is a detail of the same mechanism as shown 70 in Fig. 6, the gages being shown lifted and about to be returned to their operating position.

In the embodiment of the invention illustrated in the drawings the general construction of the machine head is the same as is illustrated in said Hadaway Patent No. 1,087,578. The parts which have not been altered may briefly be referred to (see Fig. 75 1) as the head casting 2 which receives the driving shaft 4 driven by a belt over the pulley 6; the reciprocatory head 8 actuated by the crank pin 10 on the forward end of the shaft 4; the work table 12 carrying the toe gage 14 and yieldingly supported upon 80 the spring 16; and the one revolution starting and stopping mechanism generally indicated by 18 controlled by a treadle attached to the treadle rod 20.

The present machine is designed to produce a different type of sole than is produced by the old machine and to this end changes and improvements have been made in the form and mounting of the knives carried by the reciprocatory head 8. Referring 95 more particularly to Figs. 2 and 3, the head 8 is provided with a central slot 22 which receives a presser foot 24 of the same form as the presser foot in said Hadaway patent. The presser foot 24 is adjustably held 100 in place by a headed screw 26 passed transversely through a vertical slot 28 in the foot and also through a collar 30, supported in a bore in the head 8, which acts to clamp the presser foot against one side of the slot 105 22 when the screw 26 is tightened. On either side of the presser foot 24 are the knife blocks which carry the knives 32 and 34.

The knife 32 is shaped to produce a V-shaped incision 90 at the tip of the toe of a sole placed upon the work table, and is provided with a cylindrical shank received in a vertical bore 36 in the lower face of the knife block 38. The knife 32 is held in the block by a set screw 40 and the knife block is held to the head 8 by a headed screw 42. The connection between the head 8 and the knife block 38 is by means of a horizontal tongue on the head fitting into a complementary groove on the block as shown in Fig. 3, which prevents vertical displacement between these two parts and permits transverse adjustment. The knife blade 34 which is shaped to produce a lineal incision 92 in the sole at the rear of the V-shaped incision 90, unlike the knife 32, is separable from its shank. This blade is adjustably secured within the angle of an angle piece 44 at the lower end of the cylindrical shank 46. The adjustment is secured by loosening a set screw 48 which is threaded into the angle piece 44 through a horizontal slot 50 in the blade 34. The shank 46 is held by a set screw 47 in a bore 52 in a knife block 54 mounted on the side of the head 8 opposite the knife block 38 and in like manner. Like the block 38 the headed screw 56 which secures the block to the head is passed through a horizontal slot 58 (Fig. 2) thus permitting a transverse adjustment of the knife blade 34 on the tongue and groove connection.

35 It will be noted that the manner in which the shank 46 of the knife 34 is supported in its knife block 54 permits an angular adjustment of the knife 34 with respect to the knife 32. So that the incision made by the knife 34 will extend across the median line of the sole as is shown in Fig. 4 and as will be explained later.

40 The position of the sole relative to the knives 32 and 34 is gaged by the toe gage 14 and two forepart gages 60 and 61 which overlie the upper face of the table 12. These forepart gages have the form of bars, the outer ends of which extend beyond the edge of the table and are connected respectively to the outer ends of the two gage arms 62 and 63, the inner ends of which are loose upon vertical pivot pins 64 and 65 threaded into the lower face of the table 12. The connection between the gages and gage arms is such that there is no relative movement between these parts as is clearly indicated in Figs. 4 and 5. The gage arms 62 and 63 are provided at their inner ends with intermeshing toothed segments 66 and 67, so that the gages 60 and 61 move together and equally. Coiled about both pivot pins 64 and 65 is a continuous wire spring 68, shown by dotted lines in Figs. 4 and 5, the ends of which engage the forward sides of pins 70 and 71 on the upper sides of the gage arms

62 and 63. This spring continually tends to urge the forepart gages toward each other. An adjustable stop screw 72 threaded through a lug on one edge of the table 12 limits the inward movement of the forepart gages by engagement of the gage arm 71 therewith. This gage arm is also provided with a handle 74 by which the gages may be moved apart against the force of the spring 68. Beneath the work table 12 are secured two leaf springs 76 and 77 (dotted lines Figs. 4 and 5 and full lines Figs. 6 and 7) by screws 78 and 79 at their rear ends, their forward ends being forked and embracing the pivot pins 64 and 65. 80 These leaf springs bear downwardly upon the coils of the wire spring 68 and thus continually tend to press the two gage arms, and consequently the forepart gages, downward. The effect of this construction is that 85 as soon as the gages 60 and 61 have been withdrawn beyond the edge of the table by pulling upon the handle 74, the leaf springs immediately and automatically press the gages downward as far as is permitted by 90 the heads of the pivot pins 64 and 65, that is, to a position to or below the level of the upper face of the table 12. The wire spring 68 maintains the gages in this inoperative position by forcing them against the edges 95 of the table 12.

Depending from the table 12 is a gage repositioning member which comprises a handle 80 and a tail plate 82, the latter extending toward the pivot pins 64 and 65 100 and recessed at its edge to embrace both of these pins below the gage arms 62 and 63 (see dotted lines, Figs. 4 and 5). The handle 80 of this member is provided with a central boss which is positioned between bosses 105 84 on the lower face of the table. A pintle 86 held in the handle 80 by a set screw 88 extends through all the bosses thus hinging the gage repositioning member on the table. By knocking the handle 80 inward, 110 the tail plate 82 is rocked upward and the gage arms 62 and 63 are thus lifted against the force of the leaf springs 76 and 77 and immediately the gages 60 and 61 arrive above the upper face of the table 12, the 115 coiled wire spring 68 moves them across the table into operative position.

The reason for the novel gage mounting just described, is to provide, at times, a work table the surface of which is entirely 120 free of obstruction, thus permitting a free manipulation of the sole over the work table and relative to the knives on the reciprocating head 8. For the operation that is called toe snipping, the forepart gages 60 125 and 61 remain in their operative position as shown in Fig. 4, and the toe of the sole is placed between them, its tip being in contact with the toe gage 14. The two cuts heretofore described may then be made by 130

a reciprocation of the head 8. It is found desirable, however, to make an additional cut in the margin of the sole through the stock which forms the channel flap at the 5 inside ball where the curvature is greatest, The removal of the forepart gages 60 and 61 from above the work table permits the sole to be positioned, as shown in Fig. 2, with the edge of the inside ball against the 10 toe gage 14. In order to make a cut approximately perpendicular to the gage 14 with the knife 34, it is necessary to loosen the set screw 47 and turn the shank 46 angularly until the knife stands normal to the 15 gage 14, and then loosen the screw 56 and adjust the knife block 54 laterally until the knife stands opposite the gage 14. Furthermore the set screw 40 is loosened at this 20 time and the V-shaped knife 32 is pushed upward within the bore 36 a sufficient distance to render it inoperative. Thereafter, when the head 8 is reciprocated, a single 25 incision such as is shown in Fig. 5, will be made in the sole.

In the preferable mode of operation a case of soles will have their toes incised by both knives as shown in Fig. 4, then the 30 gages 60 and 61 will be moved from their operating position and while they are held from returning to their operating position by the action of the leaf springs the soles will be passed a second time through the machine to receive an incision from the 35 knife 34 at the inside ball, as shown in Fig. 5. These two operations preferably, although not necessarily, are performed upon the sole before it is channeled, although in Fig. 5 a channeled sole is illustrated to show the notch 91 and tongue 98, between the 40 slits 95 and 97, in the completely fitted blank.

The sole produced by the machine above described and the method of making it are not claimed herein since they form the subject-matter of a divisional application, now 45 Patent No. 1,393,787, Oct. 18, 1921.

It will be observed that the various adjustments provided for the knife blade 34 permit soles of all kinds to be properly incised. The variations in toe style are accommodated by an angular adjustment of the knife shank 46, while the variations in width are accommodated by a combination of said angular adjustment and a horizontal 50 adjustment of the blade 34 on angle piece 44. Variations in the width of the between substance may also be taken care of by these adjustments, it being understood that whatever the characteristics of the sole 55 operated upon may be, the blade 34 will preferably be so located as to produce a transverse slit on the channel flap which will be complementary to the slit which will be formed by the channel knife as set forth 60 more fully in said Patent No. 1,393,787.

The nature and scope of the present invention having been indicated and the preferred embodiment of the invention having been specifically described, what is claimed as new, is:—

1. A sole fitting machine having, in combination, a work table, two power-driven knives to cooperate therewith, one of said knives being constructed and arranged to make a V-shaped incision at the tip of the toe, and the other of said knives being constructed and arranged to make a lineal incision diagonally across the median line of the sole at the rear of said V-shaped incision, and gaging means to position the sole with 75 relation to said knives.

2. A sole fitting machine having, in combination, a work table, a knife having a blade to make a lineal incision in the sole, gaging means to position the sole to receive 85 said incision within its margin at the toe, and means for supporting said knife to incise the sole diagonally across its median line.

3. A sole fitting machine having, in combination, a work table, a knife having a blade to make a lineal incision in the margin of the sole, a gage against which the edge of the sole is pressed, and means constructed and arranged to permit adjustment of said 95 knife to make an incision either diagonally or approximately perpendicularly to a tangent at the point of engagement of the gage and to secure said knife in adjusted position.

4. A sole fitting machine having, in combination, a work table, a reciprocating head to cooperate therewith, a knife carried by the head and having a blade to make a lineal incision in the margin of the sole, a gage against which the edge of the sole is pressed, 105 and means constructed and arranged to permit adjustment of said knife both angularly and transversely relative to the gage and to secure said knife in adjusted position.

5. A sole fitting machine having, in combination, a work table, a knife holder above the table, two removable knife blocks mounted directly on said holder and rigidly secured thereto, an adjustable presser-foot located in a slot in the holder between said 115 blocks, and means for clamping said foot in adjusted position.

6. A sole fitting machine having, in combination, a work table, a reciprocating head to cooperate therewith, an edge gage for the 120 tip of the toe of the sole, and a knife carried by said head and operative while the tip of the toe is engaged by said edge gage to incise the sole across the channel stock at one side of the median line of the sole.

7. A sole fitting machine having, in combination, a work table, a slotted, reciprocating knife for incising the sole, a knife holder and an angular knife bar (44, 46) angularly adjustable on said holder and within the an- 125 130

gle of which said knife fits and is laterally adjustable.

8. In a sole fitting machine having a reciprocating knife for incising the margin of the sole, a work table having a toe gage and forepart gages in advance thereof above its face, and means for removing said forepart gages from their operative position relative to the toe gage and retaining them 10 in an inoperative position.

9. In a sole fitting machine having a reciprocating knife for incising the margin of the sole, a work table having a toe gage and forepart gages in advance thereof above its

15 face, and means for removing said forepart gages from above the face of the table after a movement thereof in the plane of said face.

10. In a sole fitting machine having a reciprocating knife for incising the margin of the sole, a work table having a toe gage and forepart gages which are adjustably attached thereto, and means for removing said forepart gages from their operative position 20 relative to the toe gage without detachment from the table.

11. A sole fitting machine having, in combination, a tool for operating on the sole and a work table having forepart gages extending over the face of the table means for withdrawing said gages beyond the limits of said face, and means for depressing said gages to or below the level of said 30 face.

12. A sole fitting machine having, in combination, a tool for operating on the sole and a work table having forepart gages extending over the face of the table, means for withdrawing said gages beyond the limits of said face, means for depressing said gages to or below the level of said face, and means under the control of the operative for replacing said gages above the table. 40

13. A sole fitting machine having, in combination, a tool for operating on the sole and a work table having forepart gages extending over the face of the table, devices

tending continually to depress the gages, 50 and means to move said gages beyond the edge of the table whereupon said devices operate to depress the gages to or below the level of said face.

14. A sole fitting machine having, in combination, a tool for operating on the sole and a work table having forepart gage mechanism comprising gages overlying the table, means to withdraw said gages beyond the edge of the table, and automatically acting means operating to retain said gages in 55 their position off the table.

15. A sole fitting machine having, in combination, a reciprocating knife for incising the sole and a work table having forepart 60 gage mechanism comprising gages overlying the table, means to withdraw said gages beyond the edge of the table, automatically acting means operating to retain said gages in their position off the table and means 65 actuated by the operative for returning said gages to their operating position.

16. A sole fitting machine having, in combination, a tool for operating on the sole and a work table having forepart gage 70 mechanism comprising gage arms pivoted beneath the table carrying gages overlying the table, means operating on said arms constantly tending to depress the gages, and means for turning the arms on their pivots 75 to remove the gages from the table, whereupon said depressing means lowers the gages to or below the level of the table.

17. A sole fitting machine having, in combination, a reciprocating knife for incising 80 the sole and a work table having a pair of pivot pins projecting from its lower face, gage arms mounted thereon for both angular and vertical movement, gages carried by said arms which overlie the upper face of 85 the table, springs arranged to continually force said arms downward on their pivots, and means to move said arms upward 90 against the force of said springs.

MERTON E. JOHNSON.
